UNITED STATES PATENT OFFICE.

PASQUALE DADDIO, OF NEW YORK, N. Y.

SUCTION CLEANER.

Application filed June 26, 1923. Serial No. 647,896.

My invention relates to suction or vacuum cleaners of the type in which the apparatus is wheeled or pushed by hand over the surface to be cleaned, and is thereby caused to 5 create its own power for actuating the suction producing means, and the improvements are particularly adapted to sweepers for 10 cleaning floors or floor-coverings, though it can be applied otherwise. The objects of 15 my invention are to provide a simple, light- weight structure which is durable and not easily gotten out of order, and which is compact and comparatively small in size, and yet will produce a strong suction for drawing 20 in the dust and foreign pieces of material.

The structure comprises gearing intermediate the sustaining or ground wheels and the suction creating means, for multiplying the speed of action of said means, with 25 means for automatically connecting the driving gearing with said suction creating means, when said wheels are turned forwardly by the forward movement of the apparatus over the surface to be cleaned, and to immediately disconnect the gearing when the 30 ground-wheels come to rest or are turned backwardly in the backward movement of the apparatus, at the same time permitting said suction creating means to continue to run or operate under the momentum acquired by said forward movement of the parts. The invention further comprises a peculiar 35 form of suction device, and a novel arrangement by which the gearing is connected and disconnected, as well as other features and other details hereinafter fully described and then pointed out in the claims.

I have illustrated a type of my invention in the accompanying drawings, wherein; 40 Fig. 1, is a perspective view of a vacuum cleaner embodying my invention.

Fig. 2, shows a horizontal sectional view of the same.

Fig. 3, shows a vertical sectional view of 45 the same the plane of the section being indicated by line 3—3, in Fig. 2.

Fig. 4, shows a vertical sectional view of the same the plane of the section being indicated by line 4—4, in Fig. 3.

50 Fig. 5, is an enlarged detail view of the automatic clutch, in vertical section on a plane indicated by line 5—5, in Fig. 3.

Fig. 6, is an enlarged detail view of the 55 automatic clutch device and part of the adjacent gearing, the view being in vertical

section on a plane at right-angles to that of Fig. 5.

Fig. 7, is an enlarged sectional view of the device for closing the mouth of the dust- collecting bag, the plane of the section being 60 indicated by the line 7—7, in Fig. 1.

Referring to the drawings, 1 indicates a closed casing having a removable top 2, and within which is housed gearing which is intermediate between the sustaining or ground 65 wheels 3, 3, and the suction fan 4, which is mounted in a suction compartment 5, located at the forward end of said casing.

The supporting or ground wheels 3, 3, are made fast to a transverse shaft 6, to which 70 is secured a pawl-carrier 7, having a pawl 8, pivoted thereto and engaging the teeth of a ratchet wheel 9, which is loose on said shaft 6, and is attached to a beveled-gear 10, also loose on said shaft. The gear 10, 75 meshes with a bevel-pinion 11, secured to a shaft 12, on which is fixed a large gear wheel 13, which drives a pinion 14, secured to the shaft 15, the respective ends of which are mounted to turn in ball-bearings 16 and 80 17, to give a smooth action to its rotation. The motion of the shaft 15, is then transmitted to a gear wheel 18, fixed thereon and the gear 18, meshes with and drives a smaller gear 19, which is integral with a tubular extension or hollow shaft 20, turning loosely 85 on the shaft 21, which is connected with and drives the fan 4, the shaft 21, having a ball bearing 22.

The hollow shaft 20, forms part of the 90 automatic clutch device for connecting and disconnecting the train of gears just described with the said fan 4. This clutch device comprises a one way driving connection 95 serving to positively turn the shaft and connected fan 4, in clock-wise direction. The inner end of the tubular part 20, is provided with a member having peripheral cam surfaces or teeth 23, over which travel back and forth cam rollers or plugs 24, which are held against the cam surfaces by the wall 100 of the cup or casing 25, which is secured by pin 26, to the shaft 21. A cover plate 27, is removably placed over the open end of the cup to exclude the dirt. This one-way clutch acts 105 to drive the shaft 21, in clock-wise direction, as per the arrow in Fig. 5, whenever the ground wheels 3, 3, are moved forward, by virtue of the cam surfaces 23, wedging the rollers 24, against the wall of the cas- 110

ing 25, and clutching the latter so as to turn it and thereby drive shaft 21, in the direction stated. As soon, however, as the ground-wheels come to rest or are reversed 5 in their movement, for example when the cleaner is drawn backwardly by hand, the cam rollers are un-wedged and disengaged so as to disconnect the clutch from the fan-shaft 21, and the fan can continue its forward 10 rotation under the momentum which it has acquired when driven under positive forward movement of the connection. The disconnecting of the driving connections by the one-way acting clutch means is one of 15 the important features of my invention and particularly when this action is associated with that of the one-way drive connection of the pawl and ratchet 8 and 9, of the ground-wheel shaft 6. These one-way acting devices permit all of the gearing between 20 the two to remain at rest, whenever the ground-wheels are reversed in their motion or come to rest.

The suction creating fan 4, is provided 25 with an imperforate back plate 28, which in addition to concentrating the action of the fan at its peripheral part, also has the effect of a fly-wheel the momentum of which acts to keep the fan spinning in its forward motion after the positive driving force has been cut off by the opening of the one-way clutch. The ball-bearing 22, of the fan shaft 21 helps to prolong the free running 30 of the fan, after it has been disconnected in the manner stated.

The suction fan 4, is housed by itself in the forwardly arranged suction-compartment 29, which is detachably connected by screws 30, to the front end of the casing 1. 40 To the front of the fan compartment housing 5, is secured the inlet or suction nozzle 31, which opens at 32, directly into the suction chamber. The inlet nozzle is provided 45 with a wide mouth 33, in which is disposed an idly revolving floor brush 34, for sweeping over the surface to be cleaned and which acts in the usual manner to loosen the dirt and facilitate its removal by the suction 50 of the fan. The ends of the brush-shaft 55 carry ground-wheels 44 for driving the shaft.

A dirt discharge pipe or passage 35, leads 55 from a point on the periphery of the cylindrical fan housing 5, and tangentially thereof, and to its outer end is removably connected the dirt receiving bag 36, the upper end of which is provided with a detachable closure comprising the outwardly over-turned ends 37, 37, which are seamed and 60 form external ridges at the mouth of the bag, a U-shaped wire member 38, which is slid on and off of the end of the bag beneath said raised parts 37, so as to grip the sides of the mouth together, and a sliding clamp 65 39, U-shaped in cross-section with the ends

of its members turned inwardly at 40, to hold the wire-staple or member 38. A chain 41, connects the metal clamp 39, with the handle 42, of the machine, the lower end of the handle being secured by a thread to a swinging bracket or yoke 43, pivoted to the casing 1, of the apparatus.

In the operation of the machine it is pushed by hand over the surface to be cleaned and this forward movement turns the ground or sustaining wheels forwardly, as indicated by the adjacent arrow in Fig. 1. This movement acts to drive the gearing which multiplies the speed of the action and through the clutch on the fan-shaft 21, actuates the suction fan at a comparatively high speed which action creates the desired suction at the mouth of the nozzle and thereby draws in the dirt through the nozzle, past the fan and into the dirt retaining bag, from where it may be removed by hand from time to time.

I have found that the construction and arrangement of the cleaner as herewith shown provides a very efficient machine, and that the suction-fan will run for a considerable time and produce a substantial suction, after the speed-multiplying gearing has been disconnected upon the coming to rest of the ground-wheels or the reversal of the same. This enables the user to clean places near the wall or an obstruction which will prevent the forward movement of the machine. It will be noted that the casing 1, is closed upon all sides and that the suction-chamber 5, located forwardly thereof is a separate and distinct structure which may be removed from the main-casing. The top of the casing 1, is arched and is detachable in order to give access to the gearing within whenever desired. Each side of the arched cover 2, upon the interior is provided with a lug 44, over which snaps the bent end of a resilient strip of metal 45, secured upon the wall of the lower part of the casing. This spring acting catch may be opened by inserting a blade between the edge of the cover where it meets the casing and forcing the spring 45, inwardly out of engagement with its lug 44, as will be understood from Fig. 3.

Having thus described my invention, what I claim and desire to secure by Letters Patent is:

1. In a suction-cleaner of the class described, a driving-mechanism housing, an axle mounted in said housing and having ground-wheels secured thereto for driving it, a one-way clutch on said axle, a bevel-gear loose on said axle and connected with and actuated by said clutch, a short-shaft at right angles to said axle and provided with a small bevel-gear meshing with said bevel-gear on the axle, speed-multiplying gearing comprising a large gear-wheel fixed on said short-shaft and a counter-shaft parallel with said

short-shaft and provided with a small gear-wheel meshing with the large gear-wheel on said short-shaft, a second gear-wheel on said counter-shaft larger than the first-mentioned 5 one, a short fan-shaft parallel with said counter-shaft and provided with a small gear-wheel driven by said second gear-wheel on said counter-shaft, a one-way acting clutch on said fan-shaft serving to drive the 10 fan in one direction, said small gear-wheel on said fan-shaft being located between the fan and the one-way clutch thereon, a fan housing mounted on the forward end of said driving-mechanism housing, the said 15 fan shaft extending into said fan housing, a fan on said shaft in the fan housing and said fan housing being provided with an intake and an outlet, said outlet being adapted to be connected with a dirt collector.

20 2. In a suction cleaner of the class described, an elongated housing for housing the fan-driving mechanism, a pair of sup-

porting and mechanism driving wheels mounted at the rear end of said housing, a 25 fan casing mounted beyond and on the forward end of said housing, a suction nozzle mounted on the fan casing immediately adjacent the forward and lower extremities thereof, said nozzle terminating in rounded edges adapted to engage the surface being 30 cleaned and forming with said wheels at the rear of the housing the entire support of the apparatus on the engaged surface, and a handle member mounted to pivotally engage the opposite sides of the housing at points 35 adjacent the forward end of the housing and a substantial distance forward of the driving wheels, whereby to press the rounded edges of the nozzle-mouth into close engagement with the surface to be cleaned.

In testimony whereof, I have hereunto set my hand.

PASQUALE DADDIO.
